Primary Examiner — Robert M Spear*Assistant Examiner* — Kendra L Hamilton(74) *Attorney, Agent, or Firm* — Crowell & Moring LLP(57) **CLAIM**

The ornamental design for a tank fairing for a motor vehicle, as shown and described.

DESCRIPTION

FIG. 1 is a left, front perspective view of a first embodiment of a tank fairing for a motor vehicle according to the design; FIG. 2 is a front view thereof;

FIG. 3 is a top view thereof;

FIG. 4 is a bottom view thereof; and

FIG. 5 is a left side view thereof;

FIG. 6 is a right, front perspective view of a second embodiment of the tank fairing for a motor vehicle according to the design;

FIG. 7 is a front view thereof;

FIG. 8 is a top view thereof;

FIG. 9 is a bottom view thereof; and,

FIG. 10 is a right side view thereof.

In the drawings, the broken lines depict environmental subject matter only and form no part of the claimed design.
